UNITED STATES PATENT OFFICE.

BERNARD ARTHUR BEHREND, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

DYNAMO-ELECTRIC MACHINE.

No. 903,829.

Specification of Letters Patent.

Patented Nov. 17, 1908.

Application filed January 31, 1906. Serial No. 298,753.

To all whom it may concern:

Be it known that I, BERNARD ARTHUR BEHREND, citizen of the United States, residing at Norwood, in the county of Hamilton and State of Ohio, have invented certain new and useful Improvements in Dynamo-Electric Machines, of which the following is a full, clear, and exact specification.

My invention relates to armature cores of dynamo-electric machines and especially to the separators which are employed to divide the laminae into groups and to space them apart for the purpose of providing ventilating air passageways.

It is customary to build up armature cores of groups of laminae, which are spaced apart by separators usually segmental in shape and made of cast or sheet metal. The separators should have sufficient mechanical strength to hold the laminae a proper distance apart and should be so constructed that they will not interfere to a material extent with the free outward flow of air. A common form of separator or ventilating segment which possesses the above necessary qualities is made of cast metal, preferably brass, and consists of a number of separating or spacing ribs joined together by a web. Means should be provided for securely fastening each segment in place and for preventing outward displacement due to centrifugal force at high speeds. It has been proposed to retain the above type of segments in place by means of integrally cast lugs which engage the interior surface of the core at one or both sides of the segment. This construction, while suitable for retaining the segments in place, is objectionable for the reason that the lugs, which in the ordinary form of the segment are extensions of the narrow ribs, are easily broken off in handling or shipping, rendering the segments useless.

The object of my invention is to provide retaining means for the segments which will hold the latter securely in place without danger of outward displacement even at highest speeds and which will not be easily broken or destroyed. With this end in view, I retain the segments in place by means which engage the segments and the interior surface of the core.

More specifically considered my invention

consists in an armature core consisting of groups of laminae which are spaced apart by separating segments, each of which segments has a plurality of ribs, a certain number of which have enlarged, perforated portions extending beyond the interior surface of the core, and transverse pins engaging the perforated portions of the ribs and the interior surface of the core at each side of the segment.

My invention still further consists in the details of construction, and combinations and arrangements of parts, described in the specification and set forth in the appended claims.

For a better understanding of my invention, reference is had to the accompanying drawings, in which

Figure 1 is a section of an armature core embodying my invention; Fig. 2 is an elevation of one of the separating segments; Fig. 3 is an end view of the same; Fig. 4 is a partial elevation of a slightly modified form of segment; Fig. 5 is a section of the same; and Fig. 6 is a partial plan view of a segment showing the preferred form of holding pin.

Referring now to the figures of the drawings, I have shown at 10 a shaft of the machine carrying the spider 11, to which the armature core is secured. The armature core consists of groups of laminae 12, which are held between end heads 13 and 13^a, the former being integral with the spider and the latter being held in place by a split retaining ring 15. The groups of laminae are held a predetermined distance apart by separators 14, the number of groups and the distance at which they are held apart depending upon the size and purpose of the machine and the conditions under which it is to be operated. In this case, the separators consist of cast segments, one of which is shown in Fig. 2, which segments are arranged end to end around the core in the usual manner. The segments are preferably cast from non-magnetic metal, brass being very suitable for this purpose. As is shown in the drawing, each segment consists of a number of spaced ribs 15 joined together by an integral web 16. This construction is light, but sufficiently strong to withstand stresses due to centrifugal force, and will

not interfere seriously with the outward circulation of air.

Since the armature is rotated at considerable speed, means must be provided for preventing outward displacement of the segments due to centrifugal force. For this purpose, I provide the segments with integral lugs or enlarged portions 17 provided with perforations 18. These lugs or enlarged portions will, when the parts are assembled, extend partially beyond the interior surface of the core, and I insert in the perforation of each lug, a pin, bolt or rod 19 which will not be easily broken by a sharp blow, and in case it should be broken, it can easily be replaced at a slight cost. I have found that cotter-pins are very suitable for this purpose. Such a pin is shown in Fig. 6. As is shown in the drawing, the retaining pins extend beyond both sides of the lugs and engage closely the interior surface of the core. I prefer to form the lugs by prolonging and enlarging the inner ends of certain of the ribs, three of the ribs in this case being provided with the perforated lugs or enlarged portions. However, the lugs may extend from any part of the inner edge of the segment.

As shown in Fig. 3, the web 16 joining the ribs is flush with one side of the ribs. In Figs. 4 and 5 the web 16^a joining the ribs is in the center of the latter. Either construction may be employed, but I prefer the former construction, for the reason that it can be cast more conveniently. In the construction shown in Figs. 4 and 5, the perforated lugs are braced by extensions 20 of the web. In either construction there is less danger of the lugs being broken off than in the construction in which cast-metal retaining lugs extend outward on both sides of the ribs.

I aim in my claims to cover all modifications which do not involve a departure from the spirit and scope of my invention.

What I claim as new and desire to secure by Letters Patent is:—

1. In a dynamo-electric machine, an armature core built up of sections, separators between said sections, and separate means engaging the separators and the inner faces of the sections for retaining the separators in place.

2. In a dynamo-electric machine, a core built up of groups of laminae, separators between the said groups, each separator having an extension beyond the inner surface of the core, and a non-integral retaining pin

or rod engaging each extension and the inner surface of the core.

60

3. An armature core comprising a plurality of groups of laminae, separating segments between the groups, each segment having one or more perforated portions extending beyond the interior surface of the core, and retaining means engaging the interior surface of the core and the perforated portions of the segments.

4. An armature core comprising groups of laminae, separating segments between the groups, said segments having perforated lugs extending beyond the interior surface of the core, and retaining means passing through said perforated lugs and engaging the interior surface of the core.

75

5. An armature core comprising groups of laminae, separating segments between said groups, each of said segments having a plurality of ribs, and means engaging the inner portions of certain of said ribs and the interior surface of the core for retaining the segments in place.

80

6. An armature core comprising groups of laminae, separating segments between said groups, each of said segments having a plurality of ribs, certain of said ribs having perforated portions, and transverse pins or rods in the perforated portions and engaging the interior surface of the core.

85

7. An armature core comprising groups of laminae, separating segments between said groups, each of said segments having a plurality of ribs, certain of said ribs having enlarged perforated portions extending beyond the interior surface of the core, and transverse pins engaging said perforated portions of the ribs and the interior surface of the core.

90

8. An armature core comprising groups of laminae, separating segments between said groups, each segment consisting of a plurality of ribs joined by a narrow web or band, the inner portions of certain of said ribs having enlarged perforated portions of the same width as the ribs and extending beyond the interior surface of the core, and transverse pins or rods in said perforated portions and extending beyond each side thereof and engaging the interior surface of the core.

105

In testimony whereof I affix my signature, in the presence of two witnesses.

BERNARD ARTHUR BEHREND.
